UNITED STATES PATENT OFFICE

WILLIAM R. DONEGAN AND JOHN J. WALSH, OF HARTFORD, CONNECTICUT, ASSIGNEES
TO THE DONEGAN AUTO BODY AND SPECIALTY COMPANY, OF HARTFORD, CONNECTI-
CUT, A CORPORATION OF CONNECTICUT.

SUPPORTING MEANS FOR AUTOMOBILE-TOPS.

1,119,412.

Specification of Letters Patent.

Patented Dec. 1, 1914.

Application filed May 31, 1913. Serial No. 770,855.

To all whom it may concern:

Be it known that we, WILLIAM R. DONEGAN and JOHN J. WALSH, citizens of the United States, residing at Hartford, in the county of Hartford and State of Connecticut, have invented certain new and useful Improvements in Supporting Means for Automobile-Tops, of which the following is a specification.

10 This invention relates to supporting means for automobile tops.

In Letters Patent No. 1,046,565 granted to us on December 10, 1912 and to which reference may be had is disclosed what we term 15 for convenience a "wind shield attachment" and the present device relates generally to the class of articles shown in said prior patent.

20 One of the primary purposes of the present invention is to provide simple and effective means by which a stay rod can be quickly and readily connected with a socket member, and by which, in a certain and positive manner, the stay member and socket member will be firmly and substantially connected together when necessary, the construction being such, however, as to permit 25 the quick separation of these two parts.

Another equally important feature consists in a link connection between the stay rod and the top or equivalent part of the automobile, by virtue of which movement of the top or like part in a lateral direction will be freely permitted without the application of lateral stresses to the rod and the structure sustaining the same.

30 The organization possesses other features of novelty and utility which with the foregoing will be stated at length in the following description wherein we will set forth in detail that form of embodiment of the invention which we have selected for illustration in the drawings accompanying and forming part of the present specification, this disclosure being provided to enable those skilled in the art to practice the invention. From this it will be obvious that we do not limit ourselves to such showing; we may depart therefrom in several respects 45 within the scope of the invention defined by the claims following said description. In like manner it is not necessary that all the features of the invention be present at the same time.

Referring to said drawings: Figure 1 is a cross sectional view of the forward portion of an automobile top provided with supporting means involving our invention. Fig. 2 is a transverse section on the line 2—2 of Fig. 1. Fig. 3 is a top plan view of the supporting means. Fig. 4 is a view of a portion of the bracket and a portion of the shank of the socket member, the former being in horizontal section on the line 4—4 of Fig. 2, and the latter in plan, and being shown as occupying its operative and inoperative positions by full and dotted lines respectively. Fig. 5 is a part sectional side elevation of the supporting means, a portion only of the supporting or staymember being illustrated, and the stay member and socket member being separated, the section being on the line 5—5 of Fig. 3. Fig. 6 is a detail sectional view of the head portion of the stay rod and the latch engaged therewith. Like characters refer to like parts throughout the several figures of the drawings.

In the present case as in the patent already mentioned there are one or more brace, stay or supporting members between the body of the automobile or some other relatively stationary or rigid part thereof, and the foldable top, two of such supporting or stay members being generally employed and being preferably longitudinally adjustably connected with the wind shield as in the patent mentioned, the coöperating socket members being preferably connected with the foldable top, although in the present case as also intimated in the patent referred to this relation might be reversed, the invention not primarily concerning the connection of the stay member and socket member with any particular parts, although the best results are obtained by adjustably connecting the stay members with the wind shield, while the socket members are connected with the top.

We show none of the wind shield, although we do show a portion of the top 2 of an automobile or for that fact it might be any other vehicle. The top involves in its make up several bows only one of which is shown, being denoted by 3. We have shown only one stay member and one socket member, and its adjuncts as there may be cases where only one set of devices might

be utilized, but we prefer that the same be usually duplicated. A stay member such as meets our conditions is that denoted in a general way by 4, consisting of an elongated rod which may as shown in said prior patent be longitudinally adjustably connected with the stationary section of the wind shield of the automobile and which is also preferably situated back of the front of the top 2. The rod 4 is normally, however, immovable and may be considered practically therefore as a fixed element.

Associated with the rod is a socket member 5, approximately cylindrical and intended to receive the head 6 of the stay member or rod 4 as will hereinafter appear, said head being somewhat tapered and its apex being for convenience rounded. At the junction of the head 6 with the body of the stay member there is an annular undercut shoulder 7, the purpose of which will be hereinafter explained. The shank for said socket member 5 is designated by 8 and it is connected with the front or forward bow 3 for swinging movement, said shank having at its forward end or butt a perforation to receive the pivot 9, consisting for example of a pin or rivet extending also through holes in the inward extending lugs 10 of the bracket or plate 11 attached by screws or otherwise to the inner face of the bow 3. The outer or forward face of said bracket or plate 11 is as shown, upon an angle to fit against the correspondingly disposed adjacent face of the bow 3 to bring the pivot 9 vertical when the top 2 is up. The shank 8 as illustrated fits in the boss 12 projecting from the socket member 5, the screw 13 tapped through said boss, firmly engaging the shank 8 to thus hold the two parts in rigid relation with each other.

It will be understood that when the socket member 5 is in operative relation as shown in Figs. 1, 3 and 5, the shank 8 extends inwardly at a right angle to the bow 3. When it is desired to fold or close the top 2 it is desirable that the shank 8 and socket member 5 fold against the bow, and this is readily possible by virtue of the described hinge connection between said shank and bow, the shank being shown in its two extreme positions by full and dotted lines in Fig. 4. Means are provided for holding against accidental movement, said shank in its two positions, the spring 14 fastened by a screw 15 at one end to the plate or bracket 11, being shown for this purpose, the butt portion of the shank 8 having the flat faces 16 and 17 adapted to be alternately engaged by the free portion of the spring to insure the results in question. In Fig. 4 the free portion of the spring is shown as engaging the flat face 16 so as to maintain the shank 8 in operative relation. The shank can, however, when the socket member 5 is dis-

connected from the stay rod 4 be readily folded against the bow 3 as shown by dotted lines in said Fig. 4, and when it is the free portion of the spring will engage the flat face 17 to hold the shank 8 in its folded relation and against jarring and rattling.

The socket member 5 is shown as having a slot 18, the latch 19, pivoted between its ends as at 20, being mounted in the slot or notch 18; the lower portion of the latch 19 having a projection 21 to hook under the annular beveled shoulder 7 of the stay rod 4, the pin 22 crossing the notch 18 being adapted to limit or restrict the inward or operative movement of the latch 19. Tapped through the tail or upper portion of said latch is the screw 23, the inner portion of the shank thereof being plain and being intended to receive the coiled push spring 24 fitted partly in a bore 25 in the upper portion of the socket member 5 and which bore intersects the slot or notch 18. The head 26 of said screw 23 serves as a simple and convenient means for manipulating the latch 19.

It will be assumed that the top of the automobile has been opened and that the shank 8 has been swung away from the bow 3 and that it occupies a position at right angles thereto as shown in Fig. 1, it being further understood that the rod 4 has been adjusted to the requisite height. The forward portion of the top 2 is then drawn down, so that the tapered head 6 can enter the socket member 5, said head as it enters said socket member riding along the beveled face 27 of the latch 19 and thereby causing said latch to automatically recede until such point as the head 6 releases the latch at which time the spring 24 of said latch then under maximum compression projects the detent or projecting portion 21 under the shoulder 7 to thereby firmly connect the rod 4 and socket member 5 until such time as the latch is released by forward pressure on the finger piece or screw head 26. In Fig. 5 the head 6 is shown by dotted lines as having entered the socket member 5, but it should be understood that this entrance is accomplished by drawing down the socket member 5 and not in projecting upward the rod 4.

The shank or arm 8 and its socket member 5 present together a link pivotally connected with the stay rod 4 and the top 2 in view of which construction it will be clear that the top can freely move sidewise without applying lateral stresses to said stay rod owing to the fact that said link can swing laterally with the top during its said movement and one of the broader features of the invention is in a stay rod and a link both of any kind, wherein the link is between the stay rod and some other part, such as the top, to secure the advantage in question the axes of motion of said link being preferably approximately parallel with

the longitudinal axis of the stay rod. It is also clear that by reason of the described construction, the stay means by reason of the presence of the linkage connection, does not apply any lateral strain to the top, although the latter is at all times when the parts are operatively connected, effectually supported.

What we claim is:

6. 1. The combination of a top, a stay member, and a stiff link pivotally connected with the top and with the stay member to move laterally with the top on sidewise movement of the latter, the axes of motion of the link being transverse to the line of lateral movement of the top.
13. 2. The combination of a top, a stay rod, a link pivotally connected with the top and also pivotally connected with the stay rod, the link being provided with a spring actuated latch for detachably connecting the same with said stay rod.
20. 3. The combination of a stay rod, a top provided with a forward bow, and a socket member detachably connected with said stay rod provided with a shank movably connected with said bow to fold against the latter.
25. 4. The combination of a stay rod, a top, a link pivotally connected to the top to occupy operative and inoperative positions; said link being provided with means for its detachable connection with said stay rod, and means for holding said link in its two positions.
30. 5. The combination of a stay rod, a top, a

link pivoted to the top to occupy operative and inoperative positions, said link being provided with means for its detachable connection with said stay rod, and spring means for holding the link in its two positions.

6. The combination of a top, a stay rod, a link pivoted to the top and having a socket member to receive said stay rod, said socket member having a spring advanced latch and the rod having means for retracting the latch on the insertion of the rod into said socket member.

7. The combination of a top, a stay rod having a head provided with a shoulder, and a socket member to pivotally receive said head and provided with a spring actuated latch to engage under said shoulder said socket member also having a shank pivotally connected with said top.

8. The combination of a top, a stay rod, a socket member having a notch, the head of said stay rod being insertible into and rotative in said socket member, the latter having a shank movably connected with said top and a latch pivoted in said slot, for engaging the stay rod.

In testimony whereof we affix our signatures in presence of two witnesses.

WILLIAM R. DONEGAN.
JOHN J. WALSH.
